United States Patent Office

Des. 190,851
Patented July 11, 1961

190,851

BUILDING OR SIMILAR ARTICLE

Franklin E. Day, 243 E. Jackson St., Millersburg, Ohio,
and Glenn W. Barnett, 4517 Young Drive, Wooster, Ohio

Filed Aug. 3, 1960, Ser. No. 61,620

Term of patent 14 years

(Cl. D13—1)

FIG. 1

FIG. 2

FIG. 3

FIG. 5

FIG. 1 is a front elevation of a building embodying our novel design.

FIG. 2 is an end elevation thereof.

FIG. 3 is an elevation of the opposite end thereof.

FIG. 4 is a rear elevation.

FIG. 5 is a top plan view.

The dominant features of our design reside in the portions shown in full lines in FIGS. 1-4, inclusive.

We claim:

The ornamental design for a building or similar article, substantially as shown and described.
